[57] CLAIM

The ornamental design for a blade for a power scythe, as shown and described.

DESCRIPTION

FIG. 1 is a top plan view of a blade for a power scythe showing our new design, the undisclosed bottom side being a mirror image of the top;

FIG. 2 is a right side elevation thereof;

FIG. 3 is a cross-section taken on the line III—III of FIG. 1;

FIG. 4 is a cross-section taken on the line IV—IV of FIG. 1; and

FIG. 5 is an enlarged fragmentary cross-section taken on the line V—V of FIG. 1.

FIG. 1

*FIG. 2**FIG. 3**FIG. 4**FIG. 5*
